UNITED STATES PATENT OFFICE.

ARTHUR H. JOSEPH, OF DETROIT, MICHIGAN, ASSIGNOR TO THE MILEOMETER COMPANY, OF CHICAGO, ILLINOIS, A CORPORATION OF ILLINOIS.

SPEEDOMETER.

Application filed July 9, 1923. Serial No. 650,436.

My invention relates to that general class of devices employed for measuring and indicating speed and distances covered by vehicles, and has among its objects the production of a device of the kind described, which is simple, convenient, neat and attractive in appearance, compact, durable, reliable, accurate, efficient and satisfactory for use wherever found applicable.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts:

Fig. 1 is a sectional view taken through my device;

Fig. 2 is a sectional view taken substantially on line 2—2 of Fig. 1;

Fig. 3 is a sectional view taken substantially on line 3—3 of Fig. 1;

Fig. 4 is a sectional view taken substantially on line 4—4 of Fig. 1.

Fig. 5 is a top plan view of the speed-indicating dial moved to a different position than that shown in Fig. 2;

Fig. 6 is a sectional view taken substantially on line 6—6 of Fig. 5; and

Fig. 7 is an enlarged detail of the calibrating device.

Referring to the drawings, it may be mentioned that in the preferred construction, I provide a casing of suitable size, shape and material, comprising a hollow part 1 having a suitable covering or face plate 2 preferably removably secured thereto and provided with openings 3 through which the indicating and recording mechanisms are displayed.

A glass plate 4, or the equivalent, may cover the openings 3. The speed is indicated on a dial 5 of an indicator wheel, preferably conical in shape, and the total mileage is indicated on the odometer wheels or discs 6. The casing may have its surfaces formed for attachment to cooperating devices, as for instance route-indicating mechanisms, if so desired.

Arranged at an angle within the casing 1 and preferably projecting therefrom is a

drive shaft 16, arranged to be attached to a vehicle drive shaft connected to one of the moving parts of the vehicle (not shown). A frame 7 is removably arranged in the casing and provides bearings for the ends of the shaft 16 and carries a stationary, annularly flanged member 8 at its upper end.

A fan or impeller 9 is arranged at the inner end of the shaft 16 so as to rotate therewith, the outer ends of the impeller blades 65 being arranged adjacent the flanged periphery of the part 8, as shown in the drawings. Openings 10 are provided in the web of the flanged part 8 to permit the passage of air therethrough to the intake side of the fan. 70

Spaced at a slight distance from the fan 9 and rotatably supported independently of the drive mechanism by brackets 17, is the indicator, comprising a conical dial 5, a vane-carrying part 11 and a cam part 12. 75 The cam part 12 extends inwardly of the dial from the outer periphery to adjacent the rotational axis of the indicator and operates in a manner to be hereinafter described. The portion 11 of the indicator dial 80 is made up of a series of spaced vanes, preferably struck up from the material of the dial and having openings between adjacent vanes and through which the fluid impelled by the fan 9 is directed. 85

It will be apparent that inasmuch as the indicator is freely rotatable, the air directed by the fan will cause a rotation of the indicator dial. In order to limit the rotational movement of the indicator, an elongated opening 13 is provided therethrough and in which a stationary bar 14 projects to engage the ends of the opening, as shown more particularly in Fig. 2. 90

The blades of the fan 9 extend at approximately 60 degrees to a plane transversely perpendicular to their rotational axes, and the angle of attack of these blades are also arranged about approximately 60 degrees. The first-mentioned angle, which determines the angle of the discharge of air from the fan, has been found to give the most efficiency because it discharges the air in the angle of its natural course of flow, as it seems that air travels at said angle after it leaves the blade, regardless of the fixed shape or angle of the blade. This is believed to be due to the centrifugal action of the air caused by the blades. By so shaping the blades that the air is discharged in the angle of its nat- 100 105 110

ural course, the velocity and volume of air is increased for the same speed of fan rotation. For the same reason the receiving angle of the blades of the fan 11 are also made 5 60 degrees.

In order that the movement of the indicator will not be vibratory, but will be steady and accurate at all times and in order to retrieve the indicator to a zero position whenever the vehicle is at rest, I have arranged a 10 leaf spring 15 connected at one end to a fixed or stationary part 21, the other end of said spring being free and engageable with the cam surface of the cam 12. If desired, an 15 anti-friction member 15' may be arranged at the end of the spring 15 so as to decrease the wear between the spring and the cam.

The free end of the spring 15 is substantially at the rotational axis of the indicator 20 when the vehicle is at rest and the cam is so positioned that there will be but a small amount of friction between the cam and the spring at the low speeds, the thrust between said parts increasing as the speed increases 25 and as the cam moves the spring outwardly.

In order to adjust the spring and calibrate the indicator, fingers 22 or the like are arranged to be carried by the stationary part of the device and engage the spring at 30 various points as the spring moves outwardly.

The frame 7 carries a rotatable shaft 23 upon which the odometer wheels 6 are positioned. A shaft 24 is arranged at another part of the frame substantially parallel to the shaft 23 and carrying a gear 25 adapted to intermesh with the worm of the drive shaft 16. A gear 26 is carried by the shaft 24 and meshes with a gear 27, which, in turn, drives a gear 28 meshing with a gear 29 carried by the shaft 23 of the odometer 40 wheels 6.

It will be noted that the dial member 5 is substantially in the shape of a frustum of a cone at the face; that is, the face is at an angle to the axis of rotation, and the drive shaft 16 is inclined at an angle of 45 degrees to the plate 2 so that the point of indication on the dial, or the exposed face of 50 the dial, is substantially parallel with the face of the casing. This tends to permit a more compact construction as well as being the most convenient one for installation, and eliminates the necessity of using an angle gear, while leaving sufficient leg room clearance.

Having thus described my invention, it is obvious that various immaterial modifications may be made in the same without departing from the spirit of my invention;

hence I do not wish to be understood as limiting myself to the exact form, construction, arrangement and combination of parts herein shown and described or uses mentioned.

What I claim as new and desire to secure 65 by Letters Patent is:

1. In a device of the kind described and in combination, a drive shaft, a rotatable speed indicating dial operatively associated therewith, means independent of said dial 70 for actuating the same, and means for retarding and retrieving said dial, comprising a leaf spring fixed at one end and carrying an anti-friction member at its other end arranged substantially at the rotational axis 75 of said dial, and a cam on said dial suitably mounted and constructed to slidably engage with the free end of the spring so as to exert pressure on and distort the spring in accordance with predetermined indicated speeds 80 with the pressure of the spring reacting on the cam and tending constantly to return said dial to zero reading.

2. In a device of the kind described and in combination, a drive shaft, speed-indicating means mounted independently thereof and having vanes thereon, a fan carried by said drive shaft and arranged adjacent said vanes for controlling the operation of said speed-indicating means, and means for retarding and retrieving said dial, said retarding and said retrieving means comprising a leaf spring fixed at one end and carrying an antifriction member at its other end arranged substantially at the rotational axis 95 of said speed-indicating means, and a cam carried by said speed-indicating means to slidably engage with said anti-friction member so as to exert pressure on and distort the spring in accordance with predetermined indicated speeds with the pressure 100 of the spring reacting on the cam and tending constantly to return said dial to zero reading.

3. In a device of the character described 105 and in combination, a rotatable speed dial, means for actuating the same, a leaf spring fixed at one end, an anti-friction member at the other end of the spring, and a cam on the dial for slidably engaging the anti-friction member so as to exert pressure on and distort the spring in accordance with predetermined indicated speeds, with the pressure 110 of the spring reacting on the cam and tending constantly to return said dial to zero 115 reading.

In testimony whereof, I have hereunto signed my name.

ARTHUR H. JOSEPH.
